US0D1093382S

(12) **United States Design Patent** (10) **Patent No.:** **US D1,093,382 S**
(45) **Date of Patent:** **** Sep. 16, 2025**

(54) **WATCH**

(71) **Applicant:** **BEIJING XIAOMI MOBILE SOFTWARE CO., LTD.**, Beijing (CN)

(72) **Inventors:** **Lingzhu Shao**, Beijing (CN); **Jingfan Jiang**, Beijing (CN)

(73) **Assignee:** **BEIJING XIAOMI MOBILE SOFTWARE CO., LTD.**, Beijing (CN)

(**) **Term:** **15 Years**

(21) **Appl. No.:** **35/521,300**

(22) **Filed:** **Jun. 16, 2023**

(80) **Hague Agreement Data**

Int. Filing Date: **Jun. 16, 2023**

Int. Reg. No.: **DM/229844**

Int. Reg. Date: **Jun. 16, 2023**

Int. Reg. Pub. Date: **Jun. 21, 2024**

(30) **Foreign Application Priority Data**

Dec. 24, 2022 (CN) 202230858845.X

(51) **LOC (15) Cl.** **14-02**

(52) **U.S. Cl.**

USPC **D14/344**

(58) **Field of Classification Search**

USPC D10/30-39, 122-128, 65, 70; D14/344;
D11/3; D24/167, 186

CPC A61B 5/681; G04G 17/00; G04G 17/005;

G04G 17/08; G04G 21/00; G04G 21/02;

(57) **CLAIM**

The ornamental design for a watch as shown and described.

DESCRIPTION

1. Watch
5. Watch
- 1.1 : Front
- 1.2 : Back
- 1.3 : Left
- 1.4 : Right
- 1.5 : Top
- 1.6 : Bottom
- 1.7 : Perspective
- 1.8 : Perspective
- 5.1 : Front
- 5.2 : Back
- 5.3 : Left
- 5.4 : Right

(Continued)

5.5 : Top**5.6** : Bottom**5.7** : Perspective**5.8** : Perspective

The portions shaded gray in the reproductions illustrate unclaimed subject matter of the watch that form no part of the claimed design.

1 Claim, 16 Drawing Sheets
